UNITED STATES PATENT OFFICE

2,586,000

DIPPER-STICK CROWDING MEANS FOR EXCAVATORS

Bert Calvert, Los Angeles, Calif.

Application September 13, 1947, Serial No. 773,777

8 Claims. (Cl. 214—135)

1

This invention relates to excavating apparatus, and is particularly useful when applied to a type of excavator sometimes referred to as a "power shovel." In its construction, this type of excavator includes a boom usually mounted to swing up and down in a vertical plane, and supported on a turntable on a tractor. The boom is normally in a more or less inclined position. On its upper side, usually a bracket is secured to the boom, on which a guide or saddle is pivotally supported to have a limited swinging movement on a horizontal axis. The material such as earth, is removed or dug out by means of a dipper that is carried on a handle or "dipper-stick" that is guided through the saddle. When the dipper is digging into a bank, it is lifted by means of a fall of hoist line that runs over one or more sheaves at the peak of the boom. The main run of this lifting line is guided under a sheave on the boom, and extends back to the interior of the cab over the tractor where it runs over a drum controlled by the operator of the excavator; the other run passes around sheaves associated with the bracket, and extends up toward the upper end of the stick where it is dead-ended. By dead-ending this run on the stick at a point considerably above the level of the boom, it will be evident that when the lifting fall connected to the dipper is being raised by its drum, a certain amount of tension will be exerted in the run that is dead-ended on the stick, tending to crowd the stick downwardly; but this crowding effect is not great until there is considerable tension in the lifting fall. For this reason until the dipper has "bitten" into the material or bank that is being excavated, there is only slight tension in the fall to the dipper, and hence the crowding effect in the stick is then due merely to the weight of the stick and dipper, it being understood that at this moment the retractor cable for the stick will be permitted to run free. This retractor cable or line usually is disposed in a loop on the under side of the stick and passes around a sheave near the stick's lower end, and at its rear side. This retractor cable has its own drum, which is in the cab, and which is also controlled by the operator of the excavator.

One of the objects of this invention is to provide an excavator of this type with means for maintaining and developing a crowding force in the dipper stick, which will be more positive in its action, and which will insure that the crowding effect when the dipper digs into the material, will be sufficient to insure that the dipper will not be deflected from the arc of its swing,

2

which it should naturally have when the dipper-stick swings around the saddle pivot.

Another object of the invention is to provide means whereby the tension in the boom cable that supports the boom, can be utilized to develop a crowding force in the dipper-stick. By this means a relatively greater crowding force can be developed, and furthermore, this force increases automatically for boom positions where the axis of the boom is inclined to a relatively small angle to the ground line.

While the means that I employ for developing this necessary crowding effect in the dipper-stick, could be used as the sole means for developing this crowding movement, in the present specification and drawing I have illustrated it employed as an auxiliary crowding means supplementing the action of the usual crowding line referred to above.

20 Further objects of the invention will appear hereinafter.

The invention consists in the novel parts and combinations of parts to be described hereinafter, all of which contribute to produce an efficient dipper-stick crowding means for excavators.

A preferred embodiment of the invention is described in the following specification, while the broad scope of the invention is pointed out in the appended claims.

30 In the drawing:

Fig. 1 is a side elevation illustrating an excavator of the type referred to, and illustrating the two lines or cables that I employ for attaining the effects of this invention; in this view the other cables that are usually employed in this type of excavator, are omitted for the sake of clearness in disclosure of this invention.

Fig. 2 is a plan of the excavator illustrated in Fig. 1, but in this view for the sake of clearness, the dipper and dipper-stick are omitted. The primary purpose of this view is to clearly illustrate the roving of the boom cable, and the means which I employ with it to develop the crowding tension in the crowding line.

45 Fig. 3 is a view similar to Fig. 1, and this view not only shows the cables illustrated in Fig. 1, but also shows some of the other cables, namely, the lifting cable for the dipper, and the usually employed crowding line. This view is on a somewhat larger scale than Fig. 1, and represents the dipper about to bite into the side of an embankment, or bank of material, such as earth. In Fig. 3, one of the sheaves on the boom bracket is broken away to show a similar sheave back of it. Referring more particularly to the parts, and

especially to Figs 1 and 2, 1 indicates the cab of the excavator, which is of conventional type. This cab is mounted on a turntable 2, which is supported on a caterpillar or "cat" 3. The framing of the cab 1 supports the boom 4 to rotate on a horizontal axis at the base pin 5 so that the boom 4 can swing up or down in a substantially vertical plane when such movement is necessary. On the upper side of the boom a saddle bracket 6 is secured, and on the upper end of this bracket a guide or saddle 7 is pivotally supported on a horizontal shaft or arbor 8 that also operates as an axle or arbor for a plurality of sheaves indicated generally by the reference numeral 9. These sheaves are usually four in number, and will be referred to more specifically hereinafter. The dipper-stick 10 is guided to slide with a controlled movement through the sleeve 7, and its lower end carries the dipper 11, the cutting edge of which is provided with the usual projecting teeth 12 to facilitate the action of the dipper in digging into an embankment 13, such as illustrated.

In applying my invention to such an apparatus, I employ a boom cable A, the main run a' of which is disposed in a coil on a drum 14 in the cab 1 (see Fig. 2). This cable also includes a dead-ended run a^2 which is dead-ended at some convenient point such as the anchor 15 on the frame of the cab. These two runs a' and a^2 pass around corresponding sheaves 16 located at, or adjacent to, the peak of the boom, and from there extend, respectively, into draw runs a^3 and a^4 . These draw runs a^3 and a^4 extend back to a point over the cab where they pass around sheaves 17 and 18 carried on a shackle 19 which, as illustrated, is of T-form, the trunk of the T being provided with an eye that is anchored on an anchor hook 20 that projects up from the upper side of the cab. These sheaves 17 and 18 enable the cable between them to be disposed in a tension loop a^5 in the bight of which a sheave 21 rides, said sheave being carried on a block 22. This sheave 21 is mounted to rotate in a substantially horizontal plane, and the forward end of the block carries a similar sheave 23, which is mounted to rotate in a substantially vertical plane.

My crowding line, that gets its tension from the loop a^5 will now be described. This line is indicated generally by the reference numeral B, and most of this line is disposed in a crowding loop composed of a lower run b' and an upper run b^2 . The lower run b' passes under the lower side of one of the sheaves 9, which is indicated in Fig. 2 by the numeral 24, from which point it passes upwardly in a crowding run b^3 that is dead-ended at 25 adjacent to the upper end of the dipper-stick. The upper run b^2 of the crowding loop B extends over the upper and outer side of one of the sheaves 9 indicated particularly by the reference numeral 26 in Fig. 2, from which point it extends down in a run b^4 dead-ended at 27 on the upper side of the boom and adjacent to the bracket 6.

It will be evident by an examination of Figs. 1 and 2, that by reason of the disposition illustrated, of the cables, the weight of the boom and its load will develop tension in the tension loop a^5 and in the crowding loop composed of the runs b' and b^2 . As illustrated in Fig. 1, this would develop an unbalanced crowding force, or thrust force, acting downwardly in the stick 10. This force of course is resisted by the retractor

cable, which constitutes a part of the regular equipment of excavators of this type.

The retractor cable, and lifting cable, illustrated in Fig. 3, will now be described. The retractor cable indicated generally by the reference numeral C, includes a loop c' that extends down the under side of the dipper-stick, and extends under the sheave 28; and one of the runs forming this loop c' , passes over one of the sheaves 9 referred to above, from which it extends down in a short end c^2 that is dead-ended at 29 on the upper side of the boom. The other run of the loop c' passes over one of the sheaves 9 and extends over in a live run c^3 which passes over to its drum 30 in the cab 1. This drum 30 carries a brake drum 31, which is also indicated in dotted lines, which has a brake band 32 also indicated in dotted lines, connected to a brake lever 33. This drum 30 has a clutch (not illustrated) which, when closed, will permit the power to retract the stick and slide it up through the saddle guide 7.

The dipper line or lifting line to the dipper, will now be described. This line is indicated generally by the reference numeral D, and it includes a fall d' to the dipper sheave 34, the runs of which pass up and over two sheaves 35 mounted at the peak of the boom. One of these runs continues back as a live run d' and passes back under a sheave 36 mounted in the bracket 6, from which point it passes in a run d^2 over to its lifting drum 37, of the winch illustrated in dotted lines. The other run of the lifting cable that passes back down the boom, passes around a sheave 38 alongside of the sheave 36 from which it passes back toward the stick in a run d^3 that passes under the fourth loose sheave of the sheave group 9, from which point it passes upwardly in a dead-ended run d^4 that is dead-ended at 39 on the side of the dipper-stick near its upper end.

The mode of operation of the complete equipment with the complete cable illustrated in Fig. 3, will now be described. With the dipper 11 dropped onto the ground in the position illustrated in Fig. 3, the operator closes the clutch of the dipper hoist, which takes up cable in the loop d , and this of course rotates the dipper-stick around the axis of the arbor 8 so that the teeth 12 on the dipper, will substantially describe an arc such as illustrated by the dotted line 40, and this of course should fill the dipper. The crowding lines insure that the dipper will not be pushed back from this arc by the bank 13. This is assured by reason of the fact that the tension in the tension loop a^5 (see Fig. 2) is constantly maintained by the boom and the load carried by it. The tension in the loop a^5 will be greatest of course when the boom is disposed at a small angle to a horizontal line, and also at a time when the dipper is carrying its load. For this reason the tension in the crowding run b^3 of the crowding line B, will be increased automatically at a time when it should be at its maximum, and this crowding effect does not depend solely upon the tension existing in the dipper hoist line D. If the operator of the excavator desires to take a deeper bite with the dipper than occurs when the teeth follow the arc 40, he can do so by easing up on the retractor cable C. At this time he can, if he pleases, open the clutch for the retractor drum, and let the retractor cable pay out while being braked on its brake drum by the lever 33. In other words, by letting the normal resistance to the crowding cables yield somewhat, he can extend the dipper-stick 10 as described.

After the dipper 11 has picked up its load, of

course the operator moves the controls to rotate the excavator frame around on the turntable 2, and then dumps the load from the bottom of the dipper by the usual means, not illustrated. At all times the boom 4 can be raised or lowered as desired, and there is enough slack in the boom cable to insure that there will always be enough cable to maintain sufficient length in the tension loop a⁵.

Many other embodiments of the invention may be resorted to without departing from the spirit of the invention.

I claim as my invention:

1. In an excavator apparatus, the combination of a frame, a boom supported at its lower end on the frame, sheave means attached to the peak of the boom, a taut boom cable anchored at one end on the frame passing around said sheave means and in a run back toward the frame, means for guiding said run of the cable in a loop adjacent the frame; a dipper, and a dipper-stick carrying the same, and supported on the boom, means for taking up and paying out the boom cable at its other end, a crowding cable connected to the dipper-stick and to the boom so as to exert a downward thrust upon the same, and means associated with the crowding cable including a sheave riding in said loop for imparting tension to the crowding cable from said loop.

2. In an excavator apparatus, the combination of a frame, a boom supported at its lower end on said frame, sheave means carried on the boom adjacent its peak, a taut boom cable anchored at one end to the frame, passing around said sheave means and in a run back toward the frame, means for guiding said run of the cable in a loop adjacent the frame and extending toward the boom; a dipper, and dipper-stick carrying the same, means for guiding the dipper-stick to move transversely to the boom, a crowding cable connected to the dipper-stick and to the boom so as to exert a downward thrust upon the same, and means associated with the crowding cable including a sheave riding in said loop for imparting tension to the crowding cable from said loop.

3. In an excavator apparatus, the combination of a frame, a boom having a connection to said frame at its inner end, a boom cable, a sheave on the boom guiding the cable in a loop and a run passing back to the frame, for supporting the boom, means on the frame connected to the said run for maintaining the same taut, means for guiding the other run of said cable at a point adjacent the frame so as to form a loop therein extending toward the boom, a cable take-up hoisting drum on the frame on which the other end of said cable is coiled, means including a sheave riding on the inner side of said loop, a dipper-stick supported on the boom with a dipper on its lower end, a crowding cable, means including a sheave for guiding the same, supported on said boom adjacent the dipper-stick, said crowding cable having an upper run extending upwardly from said last named sheave along said stick and attached thereto; and having a lower run dead-ended on the boom; all of said parts co-operating so that the tension in said loop exerts a tension in the crowding cable, thereby exerting a downward thrust force in said stick to maintain the dipper against a bank being excavated.

4. In an excavator, the combination of a boom, sheaves supported on the boom adjacent its peak, a boom cable anchored at one end on the frame, and running on said sheaves, means for guiding

the boom cable so as to dispose a portion of the same in a tension loop, a drum in which the other end of the cable is wrapped for taking up and paying out the cable to raise and lower the boom, a dipper with a dipper-stick carrying the same, means for guiding the dipper-stick to slide across the boom, a crowding cable dead-ended on the said stick above the level of the said guiding means and dead-ended on the boom, said crowding cable disposed in a loop extending toward the said loop of the boom cable, and a block between said loops with sheaves thereon on which said loops run; all of said parts co-operating so that when the boom is lowered, the outward movement of the center of gravity of the boom increases the tension in said first named loop, thereby exerting force to lengthen the crowding loop and impart a crowding force to the dipper-stick.

10 5. An excavator according to claim 4, including a stick-retractor cable connected to the stick at a low point thereon, a brake-controlled drum on which the retractor cable is coiled, all of said parts co-operating to enable the operator of the excavator to pay out the retractor cable to control the crowding effect while the crowding cable is exerting a downward thrust in the dipper-stick.

15 6. In an excavator, the combination of a frame, a boom, means for supporting said boom on said frame at its lower end to enable the boom to be swung up and down in a substantially vertical plane, a boom cable anchored at one end, means mounted on the boom for engaging said cable and cooperating with the same to enable the cable to support the boom in an inclined position, a drum mounted on the frame upon which a run of said cable is coiled, for taking up or paying out cable to raise or lower said boom,

20 35 means connected with the frame for guiding the boom cable in a tension loop, a dipper-stick with a dipper carried thereby, a guide for said dipper-stick pivotally mounted on the boom, and crowding means connected to the dipper-stick and to the boom, including a sheave running in said tension loop, the tension in said loop being increased by increasing the tension in the boom cable when the boom is lowered to pick up the load, thereby increasing the crowding thrust acting on the dipper-stick so as to move the dipper forward as it takes its load.

40 50 7. In an excavator, the combination of a frame, a boom supported in said frame to swing up and down about a substantially horizontal axis, a boom cable anchored on the frame, a drum on which a run of said cable is wound for raising and lowering the boom, means adjacent the peak of the boom for guiding said cable on the boom, to enable the same to cooperate with the drum to support the boom, means supported on the frame for guiding the boom cable in a tension loop, the tension whereof is maintained by the weight of the boom, and increased by the weight of the boom when the boom is lowered to take a load

55 60 65 70 85 in the dipper, a crowding cable, means for guiding the same in a loop connected to said tension loop to maintain tension in the crowding cable; said crowding cable having a guide sheave on the boom about which it passes, means for anchoring one of the runs of the crowding cable on the boom, and means for anchoring the other run of the crowding cable on the dipper-stick.

8. In an excavator having a frame, a boom supported thereon at its lower end, and a dipper stick crowding cable, the combination of a pair

of peak sheaves supported adjacent the peak of the boom, and on opposite sides thereof, a shackle pivotally supported on the frame, a pair of sheaves spaced apart, mounted on said shackle, and a cable anchored at one end and passing around one of said first named sheaves, then back to and around one of said second pair of sheaves, then extending toward the boom on a tension loop, beyond said tension loop passing around the other sheave of said shackle, and thence passing over the other sheave and then passing in a run back toward the frame, and a take-up drum for the cable on which the last named run is wrapped.
